UNITED STATES PATENT OFFICE.

PALMER KENNEDY, OF TACOMA, WASHINGTON.

CUTTING DEVICE.

Application filed May 10, 1921. Serial No. 468,390.

To all whom it may concern:

Be it known that I, PALMER KENNEDY, a citizen of the United States, residing at Tacoma, in the county of Pierce and State 5 of Washington, have invented certain new and useful Improvements in Cutting Devices, of which the following is a specification.

My said invention relates to a holder for 10 cutting blades and is intended primarily for use in ripping seams and doing other similar light work.

It is an object of my invention to provide a device the parts of which may be 15 taken apart and put together without danger or injury to the user and which shall in general be saving and convenient in use.

Referring to the accompanying drawings 20 which are made a part hereof and on which similar reference characters indicate similar parts,

Figure 1 is an elevation of one form of my device,

25 Figure 2 is a section on line 2—2 of Figure 1,

Figure 3 is an elevation of another form,

Figure 4 is a section on line 4—4 of 30 Figure 3,

Figure 5 is an elevation of another form,

Figure 6 is a section on line 6—6 of 35 Figure 5, and

Figure 6^a is a section of a modified form.

40 In the drawings reference character 10 indicates a piece which may be stamped out of sheet metal or otherwise formed and which serves at the same time as a handle and as a means for carrying the remaining parts. The cutting device is shown at 11 and this cutting device appears in the drawings as a razor blade of the type used in the Gillette safety razor, but safety razor blades of other types, as well as 45 other cutting devices may be used as will be obvious.

In the form of my invention shown in Figure 1 the holding device 10 has a bent-over portion at 12. The blade is to be inserted 50 between this portion and the main body and a clamping member 13 forced down over the same. The clamping member will force the free edges of parts 10 and 12 down on the blade and hold the same firmly in place. Preferably I mount 55 the member 13 on a pivot as at 14 but this

is not essential as the member may be made separate and may be forced on in the manner indicated or may be moved endwise into holding position. When pivoted 60 the holding member will preferably have a rearwardly projecting lip 15 for manipulating it. If desired I may form slight elevations on the handle or the bent-over portion to cooperate with the holes in the 65 blade in positioning the blade and holding it in place.

In the modification shown in Figures 3 and 4 the handle 10 and the blade 11 are 70 similar to those of Figure 1, the bent-over portion of the handle being, however, omitted. One or more projections 16 are formed on the back of the holder to assist in positioning the blade and retaining it in place. A clip 17 engages over the 75 rear of the blade and holder and enters a longitudinal notch or depression 18 in the back of the holder to aid in holding the clip in place. This clip may be either 80 rigid or resilient and is intended to be moved endwise into the position shown, the lower edge sliding in the depression 18. A shoulder 19 is formed on the handle 10 and the clip 17, when in working position as shown in Figure 3, bears against said 85 shoulder to prevent excessive rearward movement of the clip.

In the modification shown in Figures 5 and 6 the handle comprises a blade-holding portion 10' and a folding portion 20 90 pivoted thereto and adapted when folded to serve as a guard for the blade, as in the ordinary pocket knife. A pivot 21 of any convenient type, serves to connect the parts 10' and 20. This pivot may be in the 95 form of an eyelet, whereby it may serve both as a pivot and as a means for attachment of a chain or cord whereby the device can be fastened to the clothing of the user in ordinary manner. I prefer, however, to provide a hole at the lower 100 right-hand corner of the device as shown in Figure 5 and to engage a ring in the hole. The projections 16 on the handle should be made of sufficient height to engage slight indentations in the folding portion of the handle which are formed so as to register with the projections when the folding portion is closed as shown in the drawings. A slight longitudinal rib or 110 ridge 18' on the handle holds the clip 17 in place, the lower edge of the clip engag-

ing under the ridge 18'. Such a ridge may also be substituted for the groove 18 in the modification shown in Figure 4.

Figure 6^a shows the folding device of Figure 5 formed with a groove instead of the rib 18'. The modifications shown in 5, 6 and 6^a provide a convenient device to be carried in the pocket.

Having thus fully described my said invention, what I claim as new and desire to secure by Letters Patent, is:

1. A cutting device comprising a blade-holding portion for safety-razor blades or the like, a clip to hold the blade in place, 15 said clip being movable longitudinally of said blade-holder, means on the holder to prevent transverse movement of the clip, means on the holder to limit longitudinal movement of the clip, and a folding handle 20 covering the exposed edge of the blade, said clip and folding handle each having an edge engaging with the blade holding portion and the blade respectively, substantially as set forth.
- 25 2. A cutting device comprising a blade holding portion for safety razor blades or the like, a clip movable longitudinally of said blade holder to clamp the blade thereto, projections on the holder to engage openings 30 in the blade, a folding handle covering the exposed edge of the blade, said handle having depressions also adapted for engagement by said projections, substantially as set forth.
3. A cutting device comprising a holder, 35 a separate flat blade having only one face in contact with said holder, and a clip engaging over the adjacent edges of the blade and holder, to hold the blade in place, the clip being engageable with the holder and blade 40 by a longitudinal sliding movement, and means on the holder to hold the clip against transverse movement, substantially as set forth.
4. A cutting device comprising a one- 45 piece holder, means to secure a blade to one side of the holder, a channeled handle folding over and enclosing an edge of the blade and holder, and projections on the holder to fix the plate in place and also spring out the 50 sides of the handle when in closed position, substantially as set forth.
5. A cutting device comprising a holder,

means to secure a blade to one side of the holder, a channeled handle folding over and enclosing an edge of the blade and holder, and means for spreading the sides of the handle when in closed position, whereby the handle is held in such position, substantially as set forth. 55

6. A cutting device comprising a holder, 60 a blade carried thereby, a folding channeled handle adapted to enclose the blade and holder at one edge, said holder having one or more raised portions arranged lengthwise 65 thereof to extend through holes in the blade and engage the inside of the handle to assist in holding the same in closed position, substantially as set forth. 65

7. A cutting device comprising a holder, 70 a blade carried thereby, a folding channeled handle adapted to enclose the blade and holder at one edge, there being projections along the lower edge of one of said members to engage the adjacent face of the other to hold the parts in closed position, substantially 75 as set forth. 75

8. A cutting device comprising a holder 80 for a safety razor blade, a channeled handle pivoted thereto, and adapted in one position to cover an edge of the blade and in another position extending rearwardly in line with the holder, said handle having one end offset to form wings extending at all times over the rear edge of the blade, substantially as set forth. 85

9. A cutting device comprising a holder, 90 a blade resting against the holder, a clip engaging over the adjacent edges of the blade and holder, means to hold the clip with its lower edges parallel to an edge of the blade, 95 a channeled handle pivoted to the holder and adapted to enclose the opposite edges of the holder and the blade, the edges of the channeled handle adapted to rest closely against those of the clip, substantially as set forth. 95

In witness whereof, I have hereunto set my hand and seal at Washington, District of Columbia this 6th day of May, A. D. nineteen hundred and twenty-one.

PALMER KENNEDY. [L. s.]
